UNITED STATES PATENT OFFICE

EMERY J. COLLYER, OF HENRYETTA, OKLAHOMA

ENGINE

Application filed March 11, 1930. Serial No. 434,933.

This invention relates to steam engines and has as its primary object to provide a steam engine embodying a power transmitting means which will be devoid of cranks, so that the shaft which is driven by the engine will have imparted to it a continuous rotative movement at a uniform rate of speed and with a uniform application of power, and therefore differs from an engine in which power is transmitted by means of a crank shaft driven by the piston rod or rods of the engine.

Another object of the invention is to provide a power transmitting means so constructed that maximum power will be obtained by the consumption of a minimum quantity of steam, so that greater power and leverage may be obtained by the apparatus embodying the invention than by a power transmitting mechanism of the crank shaft type.

Another object of the invention is to provide a power transmission means so constructed that the engine will more effectually and more readily overcome the load than in ordinary engines of this type, and the mechanism is therefore adapted to deliver maximum power at a slow speed.

Another object of the invention is to provide a power transmission mechanism in which the rotative movement of the drive pulley will be uniform on all strokes of the engine piston, which is impossible by the employment of a crank shaft motion.

This invention also consists in certain other features of construction, and in the combination and arrangement of the several parts, to be hereinafter fully described, illustrated in the accompanying drawings, and specifically pointed out in the appended claim, it being understood that minor changes may be made so long as they fall within the scope of the claim.

In describing my invention in detail, reference will be had to the accompanying drawings, wherein like characters denote like or corresponding parts throughout the several views, and in which:—

Figure 1 is a view in side elevation of the

engine and motion transmitting means embodying the invention.

Figure 2 is a top plan view thereof.

Figure 3 is a vertical transverse sectional view taken substantially on the line 3—3 of Figure 1, looking in the direction indicated by the arrows, and illustrating the gearing through the medium of which power is transmitted, from the piston rod of the engine to the power shaft of the engine.

Figures 4 and 5 are sectional views taken respectively on the lines 4—4 and 5—5 of Figure 3, and illustrating the ratchet and pawl devices by which motion is transmitted from the engine to the power shaft.

Figure 6 is a vertical transverse sectional view taken substantially on the line 6—6 of Figure 2, looking in the direction indicated by the arrows.

The engine and power transmission mechanism are preferably mounted upon a base structure indicated by the numeral 1 and a frame structure 2 is mounted upon the base structure and supports the steam engine, the cylinder of which is indicated by the numeral 3 and the piston rod by the numeral 4, the valve casing of the engine being indicated by the numeral 5 and the numeral 6 indicating a steam supply pipe which leads from a boiler (not shown). The numeral 7 indicates a pair of uprights which are mounted upon one end of the base 1, and one end of the frame structure 2 is provided with downwardly extending portions 8 which are secured to the upper ends of these uprights, this portion of the frame being in this manner, braced. Bearings 9 are provided upon the uprights 8 and a shaft 10 is journalled in these bearings and has fixed upon it a fly wheel 11. A crank 12 is provided at one end of the shaft 10 and a connecting rod 13 is connected to this crank and to a cross head 14 slidably mounted between spaced members 15 upon the upper side of the frame structure 2. A bearing member 16 is secured to the upper sides of the members 15 and is provided with an opening 17 through which extends the valve rod 18 of the engine 3. A head 19 is fixed upon the valve rod 18, and a connecting rod 20 is pivotally connected with the said head, at one

end, and at its other end to the collar member of an eccentric which is indicated by the numeral 21 and the disk of which eccentric is fixed upon the shaft 10.

At this point it will be understood that, when the steam is supplied to the engine by way of the steam supply pipe 6, the piston 4 will be reciprocated and the reciprocatory motion of this piston will impart shifting movement to the cross head 14 and therefore rotary motion will be imparted to the shaft 10 to operate the valve rod 18 in consonance with the movement of the piston.

The power transmitting mechanism of the invention comprises a shaft 21' which is mounted in suitable bearings 22 upon the base frame 1 of the structure, and a pulley 23 is fixed upon one end of this shaft and constitutes means whereby power may be delivered to any mechanism or part to be driven by the engine. Segmental gears, indicated by the numeral 24, are rotatably mounted upon the shaft 21 and each gear has an arcuate series of gear teeth indicated by the numeral 25. The invention contemplates rotation of these gears, in consonance, but independently of each other, through the medium of rack bars which mesh with the gears and which will presently be more specifically described and means is therefore provided for clutching gears 24, alternately with the shaft 21. This means comprises an internal ratchet gear 26 which has a hub secured to the shaft 21 by means of a cross pin 27 and by reference to Figures 3 to 5 inclusive, it will be observed that these internal ratchet gears are arranged one at the inner side of each of the segmental gears 24, the teeth of the ratchet gears being indicated by the numeral 28 and extending in a continuous series in the instance of each gear.

As shown in Figures 4 and 5, the teeth 28 of the ratchet gears are presented in opposite directions with respect to each other. Pawls 29 are mounted upon the pins 30, in turn mounted upon the inner face of each gear 24 and springs 31 bear against abutments 32 upon the said face of each gear and against the respective pawls 29. As the teeth 28 of the ratchet gear are relatively oppositely disposed, in the instance of the two gears, the pawls 29 are likewise oppositely disposed. The numeral 33 indicates rack bars for co-action with the segmental gears 24, and one of these bars is mounted at its forward end upon the upper end of a bracket member 34 upon one end of an arm 35 which extends from one side of the cross head 14 and through a slot 36 in the respective one of the uprights 15, a similar arm 37 extending from the other side of the cross head and through a slot 38 in the other upright 15 and provided with an upwardly extending bracket member 39, it being observed by reference to Figure 6 that the bracket member 34 extends down-

wardly from the arm 35. The rack bars 33 are extended in parallel relation to each other except that they are offset with respect to each other both vertically and laterally, and the cross bar which is mounted upon the bracket member 39 is provided upon its under side with a series of rack teeth which are indicated by the numeral 33', and these teeth are adapted to mesh with the teeth of the segmental gear which is located at the same side of the machine as is the said rack bar, the end of the bar being led between rollers 40 mounted at the upper end of an upright 41 upon the base frame 1, and the other rack bar 33 is supported by a depending bracket member 34, at one end thereof and extends beneath the other one of the segmental gears as best shown in Figures 1 and 3 of the drawings, the end of this bar being passed between anti-friction rollers 42.

From the foregoing description of the invention, it will be evident that the rack bars will, in the reciprocation of the cross head 14 be reciprocated simultaneously and that in their reciprocatory motion, rotary motion will be imparted alternately by the segmental gears to the internal ratchet gears extending for approximately one quarter of the circumference of the respective gear, it will be evident that the engagement of the racks with the respective gear teeth will result in a continuous rotary motion being imparted to the shaft 21 and, inasmuch as power is applied, in the movement of the piston, in a straight line, it will be evident that the rotation of the shaft 21 will be at a uniform rate of speed. This arrangement provides for greater power being obtained even though the cylinder of the engines is of less capacity than the ordinary steam engine, as there is greater leverage obtained to overcome the resistance offered by the load, or in other words, the machine or the like to be driven by the engine. It will also be evident that rotary motion is imparted to the shaft 21 by a push and pull power transmitting means so that there is less torsional strain on the shaft and it is, as stated above, driven at a uniform rate of speed.

While the mechanism comprising the power transmitting unit of the present invention is illustrated and described herein as adapted for use in connection with a steam engine, it will be evident that it might equally as well be employed with an internal combustion engine.

What I claim is:—

An engine including a base having a power take-off shaft journaled adjacent one end thereof and provided with a belt wheel, a frame mounted on the base and extending from the other end thereof to a point intermediate the ends of said base, a reciprocating engine carried by the frame, a head secured to the engine and reciprocated there-

by, guide members on the frame for the head and having slots, laterally extending arms on the head and slidable in the slots, vertical standards on the base, rack bars slidable on the standards and arranged in a plane one above the other and laterally of each other, vertical brackets connecting the bars to the arms, segmental gears journaled on the shaft and in mesh with the rack bars, and pawl and ratchet means between the shaft and gears.

10 In testimony whereof I affix my signature.
EMERY J. COLLYER.
